2 Sheets-Sheet 2

Miss. 3

A technical drawing of a circular component, likely a filter or a similar device. The outermost ring is labeled 37. Inside this is a ring labeled 32. The innermost circular area is labeled 31. At the top, there is a central vertical tube labeled 41, with a circular cap labeled 42 at its top. A horizontal tube labeled 43 extends from the side of the central tube. At the bottom, there is a horizontal tube labeled 50, which has a circular cap labeled 51 at its left end and a small tube labeled 52 extending from its right end. Arrows labeled 5 point to the right from the top and bottom components. A small vertical line labeled 0.3 is also present.

WATER HEATING UNIT

Clarence Tompson, South Norwalk, Conn., and George Ray, Port Chester, N. Y., assignors to Ray Airconditioning Corporation, New York, N. Y., a corporation of Delaware

Application October 2, 1936, Serial No. 103,652

8 Claims. (Cl. 122—32)

Our invention relates to a water heating unit. In recent years there has been a growing tendency toward the general use of hot air furnaces due to their adaptability of conversion from a heating unit in winter to a unit for supplying cooled and conditioned air in the summer.

A common objection to many of these units now in commercial use is that a special unit deriving its heat from a source other than the furnace is required to supply the hot water for domestic or other consumption.

It is, therefore, an object of the present invention to provide a hot water heater that may be, if desired, readily associated with existing furnaces, and especially hot air furnaces, in such a manner that the heat for the hot water heater will be derived directly from the furnace.

It is a further object of the present invention to provide a hot water heater that may be readily associated with the fire chamber of a furnace in such a way that it constitutes a closure for the top thereof, and that when so associated makes possible a particularly compact and efficient combined air and water heating unit.

In realizing the objects above outlined, and other objects that will hereinafter appear, there is provided as a feature of the present invention a hot water heating unit capable of being readily associated with existing furnaces, especially hot air furnaces, the heater having a boiler adapted to be inserted in the fire chamber of the furnace and also having a steam head connected to the boiler, the latter having within it a separate water heating element adapted to be placed in a line with a source of water supply and a hot water outlet.

Still another feature of the invention resides in the provision of a water heater containing the feature above outlined and including means for enabling a ready circulation of water between the steam head and the boiler.

Other and more specific objects and features residing in advantageous forms, combinations and relations of parts will hereinafter appear.

In the drawings, which show the present preferred embodiments of my invention:

Figure 1 is a side view showing the water heater provided by the present invention, associated with a hot air furnace of a type now in general use, portions of the furnace being broken away for the purpose of a more clear illustration.

Fig. 2 is a front view of the furnace and hot water heater shown in Fig. 1.

Fig. 3 is a top view showing in detail the cool-

ing radiator which may be associated with the hot water heater.

Fig. 4 is a top view of the hot water heater, the upper portion of the steam head thereof being partially broken away for the purpose of illustrating the heating coil therein.

Fig. 5 is a sectional view taken on the line 5—5 of Fig. 4.

Fig. 6 is a side view of the hot water heater looking in the direction of the arrow 6 in Fig. 4, 10 the walls of the heater being partially removed for the purpose of a more clear illustration.

Before describing the present improvements and mode of operation thereof in detail it should be understood that the invention is not limited 15 to the details of construction and arrangement of parts shown in the accompanying drawings, which are merely illustrative of the present preferred embodiments, since the invention is capable of other embodiments, and the phraseology employed is for the purpose of description 20 and not of limitation.

Referring more particularly to the drawings there is shown, for the purposes of illustration, a hot air furnace 20 of a type now in general use having a main body shell 21 defining a fire chamber 22. A flanged opening 23, which may be closed by a fire door, not shown, enables a ready access to an oil burner, or other conventional heat producing source commonly positioned 25 within the main body shell. A flanged opening 24 in the body shell 21 and positioned below the opening 23 for the fire door is provided for creating a draft for the fire, while still another flanged opening 25 is provided above the fire door 30 opening to enable a cleaning out of the upper portion of the fire chamber.

Connected to the body shell 21 by a flue pipe 26 having communication with the upper portion of the fire chamber 22 is a conventional flue box 40 27. This flue box includes at least one air passage 28 jacketed by an enclosed chamber 29 having an inlet opening 30 adjacent its top plate 31 in communication with the flue pipe 26, and having a flanged outlet 32 adjacent its bottom plate 33 45 for communication with a chimney or the like. The heated air from the jacketed passage 28 may be carried by suitable and conventional conduits, not shown, to any desired part of the building to be heated.

In the usual construction, hot air furnaces of this general type have a top plate, integral or otherwise, serving as a closure for the top of the fire chamber, and no means is provided, deriving its heat from the furnace, for heating water for 55

washing, drinking and other similar purposes. Because of this fact it is customary to provide an auxiliary gas or electric heater with a special storage tank for supplying the needed hot water.

5 To eliminate the inconvenience resulting from the above mentioned practice and to enable a more economical supply of hot water, the present invention provides a novel hot water heating unit 34 which may be readily associated with a hot 10 air furnace, for example, of the general type illustrated. If the association is to be made with a furnace already constructed, it is merely necessary to remove the top of the furnace and to associate the water heater with the furnace in 15 such a way that it, instead of the removed top plate, constitutes a closure for the top of the fire chamber 22. If the heater is of a size smaller than the top of the furnace, then only a portion of the top plate of the furnace should be 20 cut out or otherwise removed.

The hot water heater 34 that may be thus readily associated with a hot air furnace includes a boiler 35, which, as illustrated may have a plurality of vertical fire tubes 36 therein to enable a 25 more efficient transfer of heat from the hot air and gases within the fire chamber 22. Preferably, and as shown, the boiler 35 is of such a width that when it is placed within the fire chamber it is spaced from the side walls constituting the shell 30 21 of the furnace.

Spaced upwardly from the boiler 35 is a steam head 37, which is made of such a size and shape that it will, when associated with the furnace 20, serve as a closure for the top thereof. In the 35 drawings the steam head 37, having a bottom plate 37' with a flat outer perimetric section providing an annular shoulder, is shown as of generally cylindrical shape and of such a size that it conforms exactly with the outside dimensions of the 40 body shell 21. If the horizontal cross sectional dimensions of the body shell be in excess of that of the steam head 37 then only a portion of the top plate of the furnace need be removed, it being sufficient if an opening is made that will 45 permit the boiler 35 being dropped into the fire chamber 22. If the cross sectional dimensions of the body shell be less than the steam head, then the outer portions of the head will overhang the body shell. A particularly satisfactory 50 closure may be had by welding the bottom plate 37' of the steam head to the furnace. It is thus seen that the unit is capable of use with furnaces of various sizes, both larger and smaller than the diameter of the steam head, and that the plate 55 37', in addition to serving as the bottom of the steam head, seems also as a closure for the top of the furnace with which the unit is associated.

A plurality of water tubes 38, connecting the 60 top of the boiler 35 with the bottom of the steam head 37, serve to support the boiler relative to the steam head, to properly position the boiler in the fire chamber 22, and to enable the heated water in the boiler to rise into the steam head. A connection 39 between the steam head 37 and the 65 lower portion of the boiler 35, passing outside of the body shell 21 when the unit is associated therewith, enables a ready circulation of water therebetween. This feature is especially advantageous in that the water by circulating upwardly through the water tubes 38 and downwardly through the connection 39 tends to equalize the temperature in the boiler 35 and the steam head 37 and to prevent pounding and knocking in the unit.

70 75 As shown, the connection 39 comprises a pipe

40 connected through an upper T-coupling 41 with a connection 42 to the steam head 37, and through a lower T-coupling 43 with a connection 44 to the boiler 35. A three-way valve 45, preferably located in the lower T-coupling 43, is selectively movable to one position permitting either a free circulation of water between the steam head and the boiler or enabling a concurrent draining of the steam head and the boiler through a pet cock 46 in the lower T-coupling, and to a second position, as shown in Fig. 5, enabling a replenishing of the water in the boiler 35 and steam head 37 through a pipe 47.

Positioned within the steam head 37, and in the lower portion thereof in order that it may be completely covered with the water 48, which, preferably as shown, is maintained at a level substantially one half the height of the steam head to leave a steam space thereabove, is a water heating element 49 adapted to be placed in a line with a source of water supply and with a hot water outlet. A gage 50 may be conveniently provided on the side of the steam head to indicate the level of the water therein.

The especially advantageous water heating element 49 provided by the present invention is formed as a coil 51 composed of connected upper and lower spirals 52 and 53. The ends 54 and 55 of the coil may be conveniently passed through suitable openings 56 and 57 in a plate 58 secured to the steam head 37 by a plurality of bolts 59 and serving as a closure for the flanged opening 60 in one side thereof. One end 54 of the coil 51 may be utilized as an inlet and connected to a source of water supply and the other end 55 of the coil 51 may be connected to a pipe leading to a hot water outlet, for example a faucet in the bath room or kitchen of a house.

Because of the double spiral coil used an especially efficient heat transfer is made possible from the hot water in the steam head 37 to the water in the coil 51. It is to be understood, however, that water heating elements of forms other than the coil shown may be used, even though not making possible as efficient a transfer of heat. Also, 45 because of the use of two water circuits in the heater, one to be heated directly by the hot gas in the fire chamber and the other to be indirectly heated through the medium of the first, a clean and fresh supply of hot water may be drawn 50 whenever it is so desired. Moreover, by the indirect heating of the water in the water heating element 49 a better control over the temperature of the water therein is made possible. If it is deemed 55 advisable to clean or replace the coil 51 at any time, it is merely necessary to remove the plate 58.

If desired, in order to prevent excessive overheating and to prevent the building up of a dangerous steam pressure in the steam head when the furnace is being forced on particularly cold days or when only a small amount of hot water is being used, a cooling radiator or condenser 61 of a conventional type as shown may be employed. A pipe connection 62 between the upper portion of the head 37 and the radiator 61 located thereabove carries the steam from the head 37 while a pipe connection 63 carries the condensed steam back to the boiler through the upper T-coupling 41 and the connection 39.

The radiator 61, which comprises a coil of pipe 64 carried by a frame 65 and having a plurality of heat conducting fins 66 thereon, is positioned at a slight angle so that the water condensed 70 75

therein may more readily pass back into the boiler.

In the operation of the hot water heater 34 when it is associated with a furnace in the manner illustrated in Figs. 1 and 2, the hot air and gases rising upwardly in the fire chamber pass around the boiler 35 and through the fire tubes 36 therein and then pass through the flue 26 into the flue box 27 where air is heated for distribution to various parts of a dwelling or other structure to be heated. The water in the boiler 35 thus heated by the hot air and gases in the fire chamber 22 rises through the water tubes 38 and into the steam head 37 to heat the water contained in the coil 51. The circulation of hot water between the steam head and the boiler, made possible by the connection 39, serves, as heretofore pointed out, to equalize the temperatures in the boiler and in the steam head and to prevent pounding and knocking therein.

It is thus seen that the present invention provides an especially efficient water heater, and one which may with facility be incorporated in existing furnaces, especially hot air furnaces, to eliminate the need for the use of special and costly auxiliary and separately heated units for supplying hot water.

Variations and modifications may be made within the scope of this invention and portions of the improvements may be used without others.

Having thus described the invention, what is claimed as new is:

1. A hot water heater adapted to be associated with a hot air furnace and to form a closure for the top thereof, comprising a boiler; a steam head spaced upwardly from said boiler and having a flanged opening at one side thereof, adapted to be secured to said furnace, and to form a closure for the top thereof; a removable plate closing said flanged opening; a water tube connecting the boiler and the steam head; and a water heating element in the lower portion of said steam head having an inlet portion and an outlet portion extending through said removable plate for connection to a water supply and a hot water outlet respectively.

2. A hot water heater adapted to be associated with a hot air furnace and to form a closure for the top thereof, comprising a boiler, having tubes therein for the passage of hot air and gases from the furnace; a steam head spaced upwardly from said boiler, adapted to be secured to said furnace, and to form a closure for the top thereof; a water tube connecting the boiler and the steam head; and a water heating element in the lower portion of said steam head having an inlet and outlet exterior said head adapted to be placed in a line with a water supply and a hot water outlet.

3. A hot water heater adapted to be associated with a hot air furnace having a fire chamber therein, said heater comprising a boiler; a steam head spaced upwardly from said boiler; a plate having a flat outer perimetric section, serving as a closure for the bottom of said steam head, adapted also to form a closure for the top of said furnace; a water tube connecting the upper portion of said boiler to the lower portion of said head; and a heating coil in said steam head having an inlet for connection to a water supply and an outlet for connection to a hot water outlet.

4. A hot water heater adapted to be associated with a hot air furnace having a fire chamber therein and to form a closure for the top thereof, said heater comprising a boiler; a steam head spaced upwardly from said boiler; a water tube connecting the lower portion of said head with the upper portion of said boiler; a connection between said head and the lower portion of said boiler; a three-way valve in said connection, selectively movable to positions to replenish the water in said head and said boiler and to circulate water therebetween; and a heating coil in said steam head adapted to be placed in a line with a water supply and a hot water outlet.

5. In a heating unit, the combination of a hot air furnace having a fire chamber therein; and a hot water heater, said heater comprising a boiler positioned in said fire chamber, a steam head spaced upwardly from said boiler, and secured to said furnace to form a closure for the top of said fire chamber, a water tube connecting said boiler and said steam head, and a heating coil in said steam head, adapted to be placed in a line with a water supply and a hot water outlet.

6. In a heating unit, the combination of a hot air furnace having a fire chamber therein; and a hot water heater forming a closure for the top of said chamber, said heater comprising a boiler positioned in said chamber, having a fire tube therein, a steam head spaced upwardly from said boiler and having a flanged opening at one side thereof, a removable plate closing said opening, a water tube connecting said head and said boiler, and a heating coil in said steam head, having an inlet and an outlet portion extending through said removable plate for connection to a water supply and a hot water outlet respectively.

7. In a heating unit, the combination of a hot air furnace having a fire chamber therein; and a hot water heater forming a closure for the top of said chamber, said heater comprising a boiler positioned in said fire chamber, a steam head spaced upwardly from said boiler, a water tube connecting the lower portion of said head with the upper portion of said boiler, a connection between said head and the lower portion of said boiler for the circulation of water therebetween, and a heating coil in said steam head having an inlet and an outlet for connection to a water supply and a hot water outlet respectively.

8. In a hot water heater adapted to be associated with hot air furnaces having a fire chamber therein, said heater comprising a boiler; a steam head above the boiler adapted to receive water therefrom, the water being normally maintained at a level below the top of the steam head to leave a steam space therein; a plate having a flat outer perimetric section, serving as the bottom of the steam head and adapted to form a closure for the top of furnaces of various sizes; a water connection between the upper portion of the boiler and the lower portion of the steam head; a connection between the lower portion of the boiler and the steam head for the circulation of water therebetween; and a heating coil in the steam head and below the normal water level therein, having an inlet and an outlet for connection to a water supply and a hot water outlet respectively.

CLARENCE TOMPSON.
GEORGE RAY.
